SPORT BUGGY

George Barris, Encino, Calif., assignor to Barris Buggies,
Inc., Anaheim, Calif.

Filed Nov. 24, 1969, Ser. No. 20,255

Term of patent 14 years

Int. Cl. D12—08

U.S. Cl. D14—3

FIG. 1.

FIG. 2.

FIG. 3.

FIG. 4.

FIG. 5.

FIG. 1 is a perspective view of a sport buggy embodying my new design and illustrating with particularity the front and one side of the sport buggy;

FIG. 2 is a perspective view of the sport buggy illustrating with particularity the other side and the rear of the sport buggy;

FIG. 3 is a top plan view of the sport buggy;

FIG. 4 is a front elevational view of the sport buggy; and

FIG. 5 is a rear elevational view of the sport buggy.

I claim:

The ornamental design for a sport buggy, substantially as shown.
